B. S. HARVEY

DINING CAR

Filed Sept. 19, 1923

UNITED STATES PATENT OFFICE.

BYRON S. HARVEY, OF LAKE FOREST, ILLINOIS.

DINING CAR.

Application filed September 19, 1923. Serial No. 663,564.

To all whom it may concern:

Be it known that I, BYRON S. HARVEY, a citizen of the United States, residing at Lake Forest, in the county of Lake and State of Illinois, have invented certain new and useful Improvements in Dining Cars; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to railway dining cars and the primary object thereof is to provide a novel form of dining car whereby greater convenience in handling food for the travelling public may be had. It is also the purpose of the invention to expedite the service of food in a convenient manner and to apply sanitary rules during the handling of the food, as now constructed dining cars are inadequate to take care of heavy travel due to the congestion in the small space allotted for the preparation of the food. An ordinary dining car has a seating capacity of about thirty-six people in the dining compartment and there are usually six waiters with probably an extra waiter to take care of persons in the Pullmans. However the space allotted to the preparation of the food is so small that usually only three men or possibly four can occupy the pantry at one time. The congestion in the diner is aggravated by the fact that there is a long passageway leading from the end of the car into the dining compartment and this is usually filled with people waiting an opportunity to be served. As a result the movements of the waiters are materially hampered and much unnecessary delay occurs which can be relieved by a dining car constructed in accordance with my invention.

My invention contemplates a dining car in which the diners are admitted from one end of the car only, the other end being occupied exclusively by the kitchen space and the pantry space so that the kitchen and pantry are the full width of the car, thereby relieving congestion and permitting the expeditious preparation and serving of the food, due to the fact that a greater space is provided for the attendants. Due to the novel construction of my invention the

kitchen and pantry may be provided with windows so that air may pass transversely through both the kitchen and the pantry which adds materially to the comfort in the attendance of the preparation of the food before it is carried into the dining compartment. My invention contemplates the provision of a compact conveniently accessible arrangement of provision bins, refrigerators, serving paraphernalia and dish racks, all of which will be clearly apparent by reference to the following description in connection with the accompanying drawings in which:

Figure 1 is a plan view of a dining car constructed in accordance with my invention.

Fig. 2 is an enlarged plan view of the end having the kitchen and pantry space.

The car is divided into three main compartments, a kitchen compartment 1, a pantry compartment 2 and a dining compartment 3, intercommunicating. The kitchen and pantry like the dining compartment extend the entire width of the car. The kitchen 1 is provided at the end of the car with two refrigerators 4 and 5 which may be filled with ice through the roof of the car. Adjacent to the refrigerator 4 is a soiled linen locker 6 and extending longitudinally of the car within the kitchen 1 and located at the side is a range 7, at the end of which is located a broiler 8 having beneath it a coal box or bin (not shown). At the opposite side of the kitchen is a compartmental receptacle 9 having a poultry compartment 10 and a fish compartment 11. The compartmental receptacle 9 is spaced away from the refrigerator 5 to provide an aisle 12 and adjacent to the compartment 10 is a milk box 13, at the end of which is located a sink 14, there being a clean dish table 15 bounded on two sides by the compartmental receptacle 9, and the milk box 13, the clean dish table being adjacent to a dish washer 16 and at the end of the dish washer is a scrap table 17, which drops on hinges to allow passageway. At the end of the kitchen, adjacent to the pantry is a steam table 18 which may be of appropriate construction and which may carry coffee urns 19 and egg boilers 20 and at the end of the steam table, I prefer to locate a sink 21, one longitudinal edge of which is a work table 22 so that the waiters can wash some of the tableware and prepare the foods such

as salads and the like in a convenient manner. Within the pantry space compartment is a substantially rectangular pantry structure 23 having an L-shaped service shelf 24, a space 25 for soiled glasses, glass stack 26 with garbage receptacle beneath (not shown). Within the structure 23 is a fruit and vegetable compartment 27 and there are additional compartments 28, 29, 30 and 31 for ice, cream and milk respectively. There is a rectangular aisle or passageway 31 entirely around the pantry structure so that access to the various compartments may be readily had. In one corner of the compartment 2 is a soiled linen closet 32 and at the opposite corner is a checker's table or shelf 34, the checker's table being adjacent to the partition 35, so that as the waiters pass out of the pantry through the opening 36 the checker may observe the food on the trays of the waiters. The kitchen is provided with windows 37, 38, 39 and 40 so that air may pass transversely through it to maintain the temperature of the kitchen below the temperature of the kitchens in the standard diners, it being a recognized fact that the kitchens in standard diners are excessively hot, particularly in warm weather. The pantry is likewise provided with ventilating windows 41 and 42 so that air may pass transversely through it and the side walls are provided with doors 43 and 44 so that access may be had to the pantry without passing through the dining compartment or through the kitchen. In the upper portion of the pantry are shelves or racks 45 and 46 (indicated with dotted lines) for canned goods and the like and in the floors of the kitchen and the pantry are trap doors 47 and 48, beneath which may be located provision bins. At the end of the car opposite to that at which the pantry and kitchen are located is a refrigerator box 49 located at one corner, which may be iced from the roof and at the opposite corner is a linen closet 50. The guests enter the diner through the door 51 at the end opposite to that which the kitchen and pantry are located, the end 52 being preferably adjacent to the baggage car so that all guests must enter the diner from one end. This prevents the congestion and confusion incident to the public crowding around the entrance to the diner so as to interfere with the attendants and waiters.

With such a construction the passage of the waiters from the dining compartment to the pantry and vice versa is entirely eliminated so that the service is expedited and in view of the fact that the pantry and kitchen occupy the entire width of the car considerable more room is provided for the attendants in the kitchen and pantry so that whereas with the standard diner only three or four waiters can occupy the pan-

try portion of the car at one time, according to my invention all six waiters (this being the usual crew) may work in the pantry at one time. This extra space in the kitchen and pantry is not at the expense of the available space in the dining compartment because a car constructed with my invention of the same length of the ordinary diner, enough space is provided in the dining compartment 3 to seat forty-two persons as against thirty-six in a standard diner and by providing a place for the checker the orders can be checked, audited, moneys received and change given by an attendant expressly provided for that purpose permitting the steward of the car to give his undivided attention to the comfort of the guests, the proper presentation of the food and other duties allotted to him. The advantage of the construction of the dining car illustrated in my drawings will be apparent when it is appreciated that under the present standard practice the waiter must wash all his own silverware before every patron whom he serves dines. He must also wash the glasses and if salad or the like order the waiter must prepare them. This causes considerable delay in the service. Under the present practice additional delay occurs because after the passenger finishes his meal there is frequently a considerable period between the time the passenger has finished and the time the dining car steward has time to audit the check, then when the waiter collects the money he takes it to the steward or lays it on the buffet at the end of the car where it is liable to remain for some time before the steward can make the change. In the meantime the waiter is probably busy in the pantry so a vexatious delay usually occurs between the time that the passenger has finished his meal and the time that he is about to leave the dining compartment. Not only is this vexatious delay irritable to the passenger but it is also irritating to those waiting to enter the diner.

With my invention these difficulties are eliminated because when a passenger enters the diner the waiter will get a duplicate check from the checker, the passenger will write his order and then the waiter will take the manifoldeed copy immediately to the kitchen, hands the original to the checker as he enters the doorway 36. There being a pantry man in the pantry structure 23, the waiter immediately receives his silverware, salads and the like, saving the time which would ordinarily be consumed if the waiter had to prepare these things. After the passenger has finished, the check which has already been audited by the checker is immediately accessible to the waiter so that it can be promptly presented to the passenger. The check may then be promptly

presented to the checker, change made and the transaction between the dining car attendants and the passenger quickly consummated. The checker is not only available 5 for making change, auditing etc., but he is also able to supervise the food as it passes from the pantry to the diner so that liability of unsatisfactory food or carelessly prepared food being served to the passenger will be entirely eliminated, the steward being relieved of some of his present duties and having an opportunity to more closely supervise 10 the comfort of the passengers in the diner and due to the fact that the serving of the meal is materially expedited, a greater number of persons can be served in a given time than is possible with the standard equipment.

What I claim and desire to secure by 20 Letters Patent is:

1. A railway car, divided into a dining compartment, a pantry compartment and a kitchen compartment, the several compartments extending entirely across the car, the 25 guest entrance of the dining compartment being at the end distant from the kitchen compartment and the pantry compartment.
2. A railway car, divided into a dining compartment, a pantry compartment and a 30 kitchen compartment, the several compartments extending entirely across the car, a pantry man's service structure in the center of the pantry compartment with a passageway extending entirely around the structure.
3. A railway car, divided into a dining compartment, a pantry compartment and a kitchen compartment, the several compartments extending entirely across the car, the 35 pantry compartment being between the kitchen and the dining compartment.
4. A railway car, divided into a dining compartment, a kitchen compartment and a 40 pantry compartment, the several compartments

extending entirely across the car, a steam table dividing the kitchen compartment from the pantry compartment, and a pantry man's service structure in the pantry compartment and having a passageway entirely around it. 45

5. A railway car, divided into a dining compartment, a pantry compartment, and a kitchen compartment, the several compartments extending entirely across the car, and a checker's station in the pantry compartment. 50

6. A railway car divided into a dining compartment, a pantry compartment and a kitchen compartment, the several compartments extending entirely across the car, a pantry man's service structure in the center 55 of the pantry compartment, and a checker's station in the pantry compartment.

7. A railway car having a dining compartment at one end and a kitchen and pantry at the other, the dining compartment 60 having a passenger entrance at one end only located distant from the kitchen and pantry end.

8. A railway car having a dining compartment at one end and a kitchen and 65 pantry at the other, the kitchen extending entirely across the car, a pantry man's service structure within the pantry and a checker's station within the pantry compartment. 70

9. A railway car having a dining compartment, a pantry compartment and a kitchen compartment, the kitchen having a center aisle, a centrally located pantry service station in the pantry compartment, a 75 steam table transversely located between the kitchen compartment and the pantry compartment, and a checker's station in the pantry compartment. 80

In testimony whereof I affix my signature.
BYRON S. HARVEY.
